INVENTOR

T. W. S. Hutchins.

BY H. R. Kerslake
ATTORNEY

UNITED STATES PATENT OFFICE.

THOMAS WILLIAM STAINER HUTCHINS, OF MIDDLEWICH, ENGLAND.

MANUFACTURE OF LAMPBLACK.

1,309,070.

Specification of Letters Patent.

Patented July 8, 1919.

Application filed October 16, 1918. Serial No. 258,452.

To all whom it may concern:

Be it known that I, THOMAS WILLIAM STAINER HUTCHINS, of Electro Bleach and By-Products Limited, of Middlewich, in the county of Chester, England, a subject of the King of Great Britain and Ireland, have invented certain new and useful Improvements in the Manufacture of Lampblack, of which the following is a specification.

10 This invention has for its object to provide new or improved means for use in the manufacture of lampblack by subjecting tar or oil to sudden intense heat, the said means permitting of the ready collection of the 15 lampblack formed and recovery of the gases produced during the heating of the tar or oil.

The invention comprises essentially the combination with a trough or vessel containing the tar or oil to be treated, of a disk 20 adapted to be rotated and so disposed that in its rotation it carries on its periphery a film of the tar or oil picked up from the aforesaid trough or vessel and means for subjecting such film upon the disk to the intense heat of one or more electric arcs, whereby lampblack is produced.

25 My invention further comprises the arrangement wherein the disk itself forms one 30 of the arc electrodes.

My invention further comprises the details hereinafter described for blowing or concentrating the arc upon the disk, for collecting the lampblack and for recovering 35 the permanent gases produced during the process.

Referring to the accompanying sheet of explanatory diagrams:—

Figure 1 is a side elevation and Fig. 2 an 40 end elevation representing one simple form of the apparatus as constructed in accordance with this invention; Fig. 3 is a side elevation and Fig. 4 a plan representing another form.

45 Fig. 5 is an elevation representing a form of the apparatus as provided with means for collecting the lampblack and also for recovering the permanent gases produced during the process.

50 The same reference letters in the different views indicate the same or similar parts.

In one convenient application of my invention, I provide as illustrated at Figs. 1 and 2, a disk or wheel *a* which may be made 55 of carbon or graphite and which dips into

a bath *b* of tar or oil, so that as the disk rotates, a film of the tar or oil is carried around upon and near the periphery of the disk. At a point adjacent said periphery and preferably at right angles to the axis 60 of rotation of the disk, I provide a carbon rod *c* through which an electric current is passed so as to form an arc between the rod and disk, the return current from the latter passing out of the apparatus by way 65 of the brush or contact *d*. The film of tar or oil is thus brought rapidly into the intensely hot zone of the arc and becomes converted into lampblack with the evolution of 70 gas.

Instead of making the disk or wheel *a* of carbon or graphite, it may be made of a vitreous or other material, the arc being then formed between two carbon rods *c*, *c'* so adjusted that the arc is projected forward onto the periphery of the disk. Or I may employ a magnet as *e* in the known manner for blowing or projecting the arc in the desired direction, such magnet being 75 coupled in series with the poles *c*, *c'* of the 80 arc as shown in Fig. 4.

In order to collect the lampblack and gas, I inclose the apparatus in an air-tight casing or housing and provide for the circulation of the gas through the latter by means 85 of a fan *g* or the like, which draws the lampblack and gas through a pipe *h* and returns the gas or a portion thereof to the said casing. The lampblack is separated from the gas by a bag or like filter *i*. The excess of 90 gas beyond the volume or capacity of the casing is tapped or drawn off, either continuously or at intervals through a valve or connection *j* and so recovered.

A gas holder or balancer as *k* is arranged 95 in a holder *l* containing liquid to form a seal.

With my improved means, the tar or oil is brought while in the form of a thin film, suddenly into the intensely hot zone of the 100 electric arc, resulting in a high yield of comparatively pure lampblack.

Having now described my invention what I claim as new and desire to secure by Letters Patent is:—

1. In the manufacture of lampblack from tar or oil, the combination with a vessel containing the said liquid, of means for picking up the liquid from the said vessel in a film form, and an electric arc projected on 110

to said film carrying means and subjecting said film to the heat of the arc, as set forth.

- 5 2. In the manufacture of lampblack from tar or oil, the combination with a vessel containing the said liquid, of a rotatable disk picking up the liquid from the said vessel in a film form, and an electric arc projected on to the disk and subjecting said film to the heat of the arc, as set forth.
- 10 3. In the manufacture of lampblack from tar or oil, the combination with a vessel containing the said liquid, of a rotatable disk picking up the liquid from the said vessel in a film form, an electric arc, and

means for projecting the arc on to the disk, 15 as set forth.

4. In the manufacture of lampblack from tar or oil, the combination consisting of a vessel containing the said liquid, a rotatable disk picking up the liquid from the said vessel in a film form, an electric arc projected on to the disk and subjecting said film to the heat of the arc and means for separating and collecting the resulting lampblack and gases, as set forth. 20 25

In testimony whereof I have signed my name to this specification.

THOMAS WILLIAM STAINER HUTCHINS.
